UNITED STATES PATENT OFFICE.

JOHN F. O'CONNOR, OF CHICAGO, ILLINOIS, ASSIGNOR, BY MESNE ASSIGNMENTS, TO
W. H. MINER, INC., A CORPORATION OF DELAWARE.

YOKE.

Application filed March 16, 1923. Serial No. 625,459.

To all whom it may concern:

Be it known that I, JOHN F. O'CONNOR, a citizen of the United States, residing at Chicago, in the county of Cook and State 5 of Illinois, have invented a certain new and useful Improvement in Yokes, of which the following is a full, clear, concise, and exact description, reference being had to the accompanying drawings, forming a part of 10 this specification.

This invention relates to improvements in yokes.

One object of the invention is to provide a yoke for railway draft riggings which is 15 of strong, durable and relatively inexpensive construction.

A specific object of the invention is to provide a draft rigging yoke wherein the parts may be readily assembled and disassembled, and more particularly such a yoke 20 for tandem gears.

In the drawing forming a part of this specification, Figure 1 is a side elevation of a yoke showing my improvements therein. 25 Figure 2 is a top plan view of the arrangement shown in Figure 1. Figures 3 and 4 are horizontal and vertical sectional views, respectively, taken on the lines 3-3 and 4-4 of Figure 1. Figure 5 is a top plan view of the rear end of the yoke showing a modified form of connector, and Figure 6 is a vertical sectional view taken on the line 30 6-6 of Figure 5.

Referring first to the construction illustrated in Figures 1 to 4, inclusive, 35 10 indicates the shank of a standard draw bar, the same having a butt 11 of usual construction, the draw bar shank being slotted to accommodate a coupler key 12.

The improved yoke, as shown, comprises, broadly, a head A; two like arms B-B; and a rear connector C.

The head A, preferably in the form of a casting, is of approximately box-like form 45 having top and bottom walls 13-13; and side walls 14-14, the latter being flared forwardly, as customary in the art. The top and bottom walls 13 are made comparatively thick, and each is provided on its inner face with a substantially U-shaped groove or recess 15, thus leaving a heavy lug 16 having a front pulling shoulder 17 and a rearwardly facing bearing or pushing shoulder 18, providing forward and rear 50 abutments for co-operation with the yoke 55

arms B as hereinafter described. The side walls 14 are suitably apertured to accommodate the coupler key 12.

The arms B are of like construction and each is preferably in the form of an elongated link with spaced arms 19-19 and loop-shaped ends 20 and 21. The thickness of the metal comprising the arms B is made to correspond with the depth of the U-shaped grooves 15, so that the forward 60 looped ends 20 of the arms fit snugly within the recesses 15, with the opposed faces of the arms B lying flush with the inner faces of the top and bottom walls of the head A. When the arms are assembled with the head A, as just described, they are held in operative position when the butt 11 of the draw bar or coupler is inserted within the head, as will be obvious from an inspection of Figure 1. With this arrangement, it is evident that, upon a draft action, the arms B will be pulled by the lugs 16 having the pulling shoulders 17. In turn, the arms B will be positively pushed by the shoulders 18 engaging the forward edges of 65 the loop ends 20.

Intermediate their ends, each branch of each arm B, may be provided with an integral vertically extending lug 22, of a longitudinal dimension corresponding to the usual distance allowed between the intermediate followers 23-23, so that they will actuate the intermediate followers in 70 75 the proper manner.

The connector C, as shown, is preferably 90 in the form of a casting and has a front, relatively wide wall 24, adapted to engage the rear main follower 25 in pulling. Above and below the plate section 24, the connector C is formed with upwardly and 95 downwardly extending lugs 26-26, of a section to fit within the loop ends 21 of the arms B and preferably the section of the lugs 26 is continued at the rear of the plate section 24, to provide the necessary 100 strength. The connector C is held assembled with the arms B by any suitable means such as cotters 27-27.

With the arrangement shown and described, it will be evident that all of the 105 parts of the yoke are of simple construction, may be manufactured at small expense, and are readily assembled and disassembled.

In the arrangement shown in Figures 5 and 6, the head and yoke arms B will be 110

the same as in the form shown in Figures 1 to 4 inclusive. The rear connector C', however, is made somewhat different, and is of rectangular form having vertical side walls 28-28, top and bottom connecting walls 29-29 and oppositely extending, centrally disposed, interior lugs 30-30, having a space between their opposed ends sufficient to permit the insertion of the arms 10 B' therebetween. The lugs 30 are of such contour as to fit within the loop-shaped ends of the arms B' and in assembling the parts, first one arm B' is inserted within the connector C' and dropped downwardly over the 15 lower lug 30 and then the other arm B' is inserted and lifted up over the upper lug 30, the parts being then held in assembled position when the followers are placed between the yoke arms.

20 I have herein shown and described what I now consider the preferred manner of carrying out my invention, but the same is by way of description and not by way of limitation, and all changes and modifications are contemplated that come within the scope of the claims appended hereto.

I claim:

1. In a yoke, the combination with a hollow head adapted to receive and be attached to a coupler butt, said head having opposed lugs; of a pair of yoke arms each having a loop formed at its front end and arranged to detachably fit over one of the lugs of said head; and detachable means 35 for connecting the rear ends of said arms.

2. In a yoke, the combination with a hollow head having interior spaced abutments at the opposite sides thereof, said head being adapted for the reception of a coupler butt 40 therebetween; of a pair of yoke arms, each being of elongated loop formation adapted to engage with the spaced abutments of said head, whereby said yoke arms are pulled or pushed upon movement of said 45 head; and a coupler butt operatively associated with said head and interposed between said yoke arms for maintaining the same in assembled relation.

3. In a yoke, the combination with a hollow head having oppositely disposed lugs; of a pair of yoke arms each of elongated link form and adapted to fit over, at its front end, one of the lugs of said head; and an independent connecting member at the 55 rear ends of said arms, arranged to fit within the ends thereof.

4. In a yoke, the combination with a hollow head adapted to receive a coupler butt therewithin, said head being provided with 60 interior abutting elements; of separate unitary yoke arms having means at their front ends detachably associated with said abut-

ting elements, said abutting elements being arranged to impart pushing and pulling movements to said yoke arms upon actuation of said head; a coupler butt operatively associated with said head and interposed between said yoke arms to maintain the same in assembled relation; and means detachably connecting the rear ends of said yoke arms. 65 70

5. In a yoke, the combination with a hollow head adapted to receive a coupler butt therewithin, said head having interior, opposed lugs; of a pair of yoke arms, each having a loop formation at its front end adapted to fit over a lug of said head, and, when in position, held assembled with the head by the coupler butt; and independent means for connecting the rear ends of said arms. 80

6. In a tandem yoke, the combination with a hollow head having substantially U-shaped recesses in the top and bottom walls thereof with the open ends of the recesses directed toward the rear of the yoke; of a pair of upper and lower yoke arms, each having a loop formation at its front end adapted to fit within one of the recesses of the head to be thereby pulled and pushed by the head when the latter is actuated; and means for detachably connecting the rear ends of said arms. 90

7. In a tandem yoke, the combination with a hollow head adapted to receive a coupler butt therewithin, the inner faces of the top and bottom walls of said head being provided with substantially U-shaped recesses, with the ends of said recesses directed toward the rear of the yoke; of upper and lower arms, each having a loop formation 100 at its front end adapted to be received within the corresponding recess of the head and held in assembled relation with the latter when the butt is within the head; and means for detachably connecting the rear ends of said arms. 105

8. In a tandem yoke, the combination with a hollow head adapted to receive a coupler butt therewithin, the top and bottom walls of said head on their inner faces being provided with substantially U-shaped recesses with the open ends thereof directed towards the rear of the yoke; of upper and lower yoke arms, each of elongated link formation and adapted, at their front ends, to fit within the recesses of the head and be held assembled with the latter when the butt is in position; and the rear connector detachably uniting the rear ends of said arms. 110 115

In witness that I claim the foregoing I have hereunto subscribed my name this 14th day of March, 1923. 120

JOHN F. O'CONNOR.
